TIME CONTROLLED ELECTRIC SWITCH

Will Green Harton, Los Angeles, Calif.

Application July 22, 1940, Serial No. 346,857

2 Claims. (Cl. 200—39)

My invention relates to an electric switch operating mechanism in combination with an alarm clock.

My invention relates to an electric switch operating mechanism in which the power to throw the switch is obtained from a manually set spring actuating a pivoted arm secured in a cocked position and released at a predetermined time by a sensitive trigger tripped by the rotation of the alarm winding key of an alarm clock.

My invention relates further to an electric switch operating mechanism having an easily removable attachment for installation over an electric toggle switch, in operable position therefore.

I attain these objects by mechanism illustrated in the accompanying drawings, in which—

Figure 1 is a side elevation of the entire mechanism set for throwing an electric switch off.

Fig. 2 is a plan view of the mechanism.

Fig. 3 is a rear elevation of the mechanism.

Fig. 4 is a plan view of the bolt and trigger movement which controls the switch throwing element, shown in a released position.

Fig. 5 is a side elevation of the mechanism with cover plate removed, shown in a position reverse from Fig. 1 as having thrown a switch on.

Fig. 6 is a side elevation of a special screw for holding the switch face plate and my switch operating mechanism.

Similar numerals refer to similar parts throughout the several views.

In as much as the device is applied to the standard electric toggle switch 2 and is combined with an ordinary alarm clock its details of construction are not shown. The invention comprises frame 1 secured at one end to the toggle switch face plate 3 by means of arm 4 above said switch and arm 4' below said switch; said frame 1 is engaged at the other end to alarm clock 5 by means of arm 6 hinged to the periphery of said clock near the back at 7 and by means of arm 6' spring secured to the periphery of said clock opposite hinge 7. Frame 1 has an open end toward switch 2. An actuating lever 8 is bent around spring 9 which engages one arm of lever 8 at 10 and also engages frame 1 at 11; said lever 8 pivoting around spring 9 describes with one end a path the circumference of which includes the toggle lever of switch 2; the other end 12 of lever 8 extends through an opening in said frame 1 to be manually operated in the development of spring tension of spring 9 and in locating the actuating end of lever 8 in an operative position. When the manually operated

end of lever 8 is pushed against spring tension to the limit of its movement it is held in this cocked position by means of bolt 13 projecting through the side of frame 1 and supported by bracket 14 and retained against withdrawal by means of pawl 15 engaging pawl 16 of trigger 17. This sensitive trigger and action is one of the features of the invention as it throws a very slight load on the bearings of the alarm winding key 18 of alarm clock 5. When in operative position at the predetermined setting of the alarm, as key 18 unwinds, one of its wings trips trigger 17, disengaging pawls 15 and 16, releasing bolt 13, allowing the operating end of lever 8 to strike 10 the toggle lever of switch 2 a hard lifting stroke from the tension of spring 9 thus throwing switch 2 which also operated on a circumference. The friction of said bolt and trigger movement is slight as bolt 13 and pawl 15 carried on pin 20 when released by pawl 16 and trigger 17, at all 15 times are moving away from lever 8, and are not required to lift any of the spring tension of spring 9 to be discharged. The contacting surfaces of pawls 15 and 16 are rounded and when 20 operating both move in the direction of a circumference, rolling on each other with no friction.

Trigger 17 from where it is contacted by alarm clock wing nut 18 to pin 21 has a long leverage which with other features set forth, assure that 25 the device may be discharged by the slight pressure of the unwinding of this wing nut 18.

Trigger spring 24 moves trigger and pawls into place when lever 8 is in a set position. Trigger spring 24 is shown in Fig. 1.

35 My device may be used to throw the switch either on or off according to the way in which it is placed over the switch. Fig. 1 shows the device ready to throw the toggle lever down, which is the usual action for throwing a switch off. This 40 will probably be the most popular use of it, in apartment halls, window signs, radios, electric stoves and heaters. By reversing the position as shown in Fig. 5 the device may be operated for throwing the switch on. Lever 8 is here shown 45 in position after having thrown switch 2.

The installation of my device is very simple; special screws 22 illustrated in Fig. 6 are provided to replace the usual ones securing face plate 3. Screws 22 have a groove around their 50 heads at 23. To install device, place the larger part of aperture 25 in arm 4 over the head of screw 22; then move the smaller part of aperture 25 into groove 23 and then swing arm 4 around so that groove 23 of the other screw fits into slot 55 26 of said arm. Clearance to permit this move-

ment of the frame is provided by making cover plate 27 shorter than the other portion of the frame as shown by dotted line 29 in Fig. 1. This clearance enables one to set the switch by hand without removing the frame from its installation. Brackets 30 are to hold cover plate 27.

I am aware that other time controlled electric switch mechanisms have been made, so that I do not claim such invention broadly; but I do claim:

1. A time controlled electric switch operating mechanism comprising an operative lever under spring tension held by a bolt in a position cocked for the throwing of a toggle switch, a trigger to release said bolt and lever operable by the unwinding of an alarm winding key of an alarm clock, said operating elements mounted in a frame having an arm with a perforation adapted

to fit into an annular groove in the head of a screw in a toggle switch face plate and a second arm having a longitudinal slot adapted to fit into an annular groove in the head of another screw in the face plate of a toggle switch for the installation of said mechanism.

2. A time controlled electric switch operating mechanism mounted in a frame removably attached to the heads of the face plate retaining screws of a toggle switch comprising a lever under spring tension positioned for throwing said toggle switch, manual means for cocking said lever to said operable position, a lever retaining bolt, a bolt releasing trigger and an alarm clock key adapted to release said trigger, bolt and lever for the throwing of said switch at a predetermined setting of said alarm clock.

WILL GREEN HARTON.
